UNITED STATES PATENT OFFICE.

BAILEY H. WEST, OF MAKANDA, ILLINOIS.

STUMP-PULLING MACHINE.

1,277,163.

Specification of Letters Patent. Patented Aug. 27, 1918.

Application filed October 31, 1917. Serial No. 199,483.

To all whom it may concern:

Be it known that I, BAILEY H. WEST, a citizen of the United States, residing at Makanda, in the county of Jackson and State of Illinois, have invented certain new and useful Improvements in Stump-Pulling Machines; and I do hereby declare the following to be a full, clear, and exact description of the invention, such as will enable others skilled in the art to which it appertains to make and use the same.

This invention relates to new and useful improvements in stump pulling machines, and the main object of the invention is to provide a machine of this character which is of simple and inexpensive construction, reliable and efficient in use.

A further object of the invention is to provide a stump pulling machine which is so constructed as to require only a minimum amount of horse power in pulling stumps of various sizes.

With these and other objects in view, as will appear as the description proceeds, the invention comprises the various novel features of construction, combination and arrangement of parts as will be more fully described hereinafter and afterward specifically claimed.

80 Referring to the drawings:

Figure 1 represents a vertical longitudinal sectional view through the stump pulling machine, and showing the same operatively associated with a stump; and

85 Fig. 2 is a top plan view of the machine.

In order that the construction and operation of the invention may be readily comprehended, I have illustrated an approved embodiment thereof in the accompanying drawings, and will now proceed to fully describe the same in connection with said drawings, in which 1 indicates a pair of parallel side bars which are connected to and supported by the front and rear axles 40 2 and 3 and constitute the main frame of the machine. Each of the axles is provided with comparatively widened supporting wheels 4 to facilitate an easy passage of the machine over soft ground.

45 50 A vertically disposed frame is mounted at the forward end of the main frame and comprises upright posts 5 which are braced and held in position by suitable braces 6. A shaft 7 is mounted in the upper ends of the posts 5 and supports a grooved sheave

8 intermediate its ends, which latter has a guard 9 extending over it and attached to the shaft 7. Mounted transversely of the vertical frame and disposed at a point immediately below the sheave 8 is a cross rod 10 to which is attached one end of a pull cable 11.

A grooved sheave 12 is mounted on a shaft 13 supported by the main frame adjacent the vertical frame and has a guard 14 extending under it and attached to the shaft 13 in the same manner as the guard 9. Another shaft 15, which is identical in construction with the shaft 12 is mounted on the main frame removed from the forward end thereof and is also provided with a guard 14.

16 indicates a cross beam mounted transversely between the side bars 1 and supports a rectangular frame 17 which is braced by suitable braces 18. 19 indicates a vertical shaft in the frame 17 and the cross bar 16 which has rigidly mounted thereon a drum 20. The upper end of the shaft 19 has rigidly attached to it a ratchet wheel 21 adapted to be engaged by a pawl 22 which serves to hold the drum against rotation in one direction. 23 indicates a stop pin to limit the swinging movement of the pawl when disengaged from the ratchet.

85 As shown the pull cable 10 is trained around the drum one or more times and is extended forwardly of the machine and has attached to it, a clevis 24 to which swing-trees 25 are connected, it being of course understood that any other suitable draft means may be attached to the clevis.

90 95 26 indicates a sheave block having a hook 27 which is adapted to engage a stump encircling element, such as a chain or the like 28. The forward end of the cable 11 is extended from the cross rod 10 around the sheave 26, over the sheave 8 and under the sheave 12 to the drum.

100 As shown the machine is adapted to be positioned relative to the stump so that the latter is in a position between the upright posts 5 so as to enable a direct upward pull to be exerted on the stump.

105 Guide rollers 29 are supported by the rectangular frames 17 and are positioned on opposite sides of the pull cable and serve to maintain the cable coiled around the drum in proper position. It is also to be noted that by virtue of the guards for each sheave, 110

the cable will be prevented from jumping off of the sheaves during the pulling of the stump.

Having described my invention, what I claim as new, is:

A portable stump pulling machine comprising a wheeled main frame, a vertical frame at the forward end of the main frame, a sheave mounted in the upper end of said vertical frame, a cross rod mounted in the vertical frame beneath said sheave, a sheave mounted at the bottom of the vertical frame, a sheave block having a hook, both of said last named sheaves mounted in a vertical plane with said upper sheave, a drum carried by the rear end of the main frame in a vertical plane with said last named sheave block, a sheave mounted on the main frame between and in longitudinal alinement with said drum and the sheave at the bottom of the vertical frame, a pull cable trained

around said drum over said last named sheave, under the sheave at the bottom of the vertical frame, over the sheave at the upper end of the vertical frame and around 25 said hook sheave block, means for rigidly attaching the terminal of the cable to said cross bar, stump encircling means adapted to be engaged by said hook sheave block, and a clevis carried by the other end of the 30 cable for the attachment of draft means, said sheaves and drum to be so arranged that the line of draft will be in a vertical plane.

In testimony whereof I have signed my 35 name to this specification in the presence of two subscribing witnesses.

BAILEY H. WEST.
